UNITED STATES PATENT OFFICE.

LESLIE S. HACKNEY, OF MINNEAPOLIS, MINNESOTA.

BED.

Application filed September 16, 1920. Serial No. 410,627.

To all whom it may concern:

Be it known that I, LESLIE S. HACKNEY, a citizen of the United States, residing at Minneapolis, in the county of Hennepin and State of Minnesota, have invented a new and useful Bed, of which the following is a specification.

My invention relates to improvements in beds.

10 Its object is to supply a simple, durable and relatively inexpensive bed capable of being conveniently folded into upright compact form and adapted, when extended for use, to slide, from position within a room 15 through an opening in the wall thereof to position exposing the head of the bed to the outer air.

A further object is to provide a folding bed of this kind adapted to protrude from a 20 side wall opening having a hinged closure therefor, said closure being connected with the frame of the bed through operating mechanism, whereby said closure is opened, when the bed is extended for use, and 25 closed and locked, when the bed is folded.

Another object is to provide a closure, as above, adapted to form a canopy, when open, the operating mechanism therefor being designed to be easily rendered inoperative to permit independent movements of 30 the closure with respect to the bed frame.

A further object is to provide for various relative adjustments between the closure and bed frame, whereby the normal positions of 35 the former with respect to the latter may be readily altered at will.

With the foregoing and other objects in view, which will appear in the following description, the invention resides in the novel 40 combination and arrangement of parts and in the details of construction hereinafter described and claimed.

In the drawings Figs. 1 and 2 are central sectional views illustrating a bed embodying my invention, the former showing the bed frame in alternate positions for use and the latter showing the bed in folded position; Fig. 3 is a detail perspective view of one end of the frame supporting beam and the arm, 50 which is attached thereto; Fig. 4 is a perspective view of the cabinet for encasing the folded bed and Fig. 5 is an elevation of the folded bed, portions of the cabinet being broken away for the sake of clearness.

55 Referring to the accompanying drawings, I have used the reference numeral 10 to indi-

cate the side-wall of a room, 11 the floor, and 12 an opening in the side wall, which may be an ordinary window opening or the like, or a specially formed opening. The numeral 13 indicates a door for said opening, said door being hinged at the top thereof and adapted not only to close the opening 12, but to form a canopy, as will hereinafter appear.

My improved device includes a pair of posts 14, a frame supporting beam A revolvable in said posts, a frame 15 slideable longitudinally on said beam and capable of being turned upward on end, extended horizontally 70 within the room or partially projected horizontally through the opening 12, mechanism for opening and closing the door, when the bed is unfolded and folded and a cabinet B for housing the folded bed.

The posts 14 are joined by a cross piece 15' and suitably anchored to the floor. The beam A comprises two plates 16 and a tie bar 17 to which said plates are secured. A pair of arms 18 are supplied, each arm having a boss 19 journaled in one of the posts 14, and formed with a square opening 20 which receives the square lug 21 on the end of one of the plates 16. Said bosses turn in the posts 14 and form a revolvable mounting 75 for the beam A.

The frame 15 is constructed of angle-iron rails and is fitted with an ordinary wire spring 22. Folding legs 23 are supplied at the foot of the frame. The depending 90 flanges, on the side rails at the head of the frame (Fig. 1), have slots 24 therein to receive the plates 16, the ends of said slots being enlarged at 25, as shown, and formed to provide catches 26 for purposes, which will 95 presently appear. In assembling the bed, the bosses 19 on the arms 18 are first inserted in bores 27 in the posts 14. The plates 16 are then passed through the slots 24 in the frame and the lugs 21 inserted in the openings 20 in the bosses 19, where they are keyed or otherwise suitably fixed. The tie bar 17 is then attached at its ends to said plates by bolts 28.

The slotted connection between the frame 105 15 and beam A permits the shifting of the frame horizontally between the two limits shown in Fig. 1. At the outer limit (solid lines), the head of the bed protrudes considerably from the opening 12 and exposes 110 the head and shoulders of an occupant to the outer atmosphere. At the inner limit (dot-

ted lines), the frame 15 rests wholly within the room. The beam A, being revoluble, permits the swinging of the frame 15 into upright position (Fig. 2). The cabinet B 5 with a doorway 29 and doors 30 therefor may be supplied to receive and enclose the bed, thus folded.

I provide for substantially counterbalancing the weight of the foot of the frame 15, 10 so that said frame may be tilted with ease. A tension spring 31 attached at one end to an arm 18 and at its other end to a post 14, pulls upon the arm and tends to turn the beam A in a direction to raise the foot of the 15 frame 15. The action of this spring has another function, namely, to tilt the plates 16 at the forward ends of the slots 24 and thus engage the beveled edges 32 of said plates with the catches 26, above mentioned. This 20 engagement of the plates 16 with said catches locks the frame 15 against sliding on the beam A and holds said frame with respect to the beam, when the bed is folded and unfolded. To release the plates 16 from 25 the catches 26 and permit the extension of the frame through the opening 12, it is only necessary for the user to pull upon the arm 18 sufficiently to overcome the action of the spring 31 and swing the plates 16 back into 30 the main slots 24.

The following mechanism is provided to open the door 13 to position forming a canopy, when the frame 15 is lowered, and to close the door when said frame is returned 35 to upright position. The parts of this mechanism are duplicated at either side of the bed and a description of one set of parts will answer for both. A lever 33 is pivoted near the middle thereof at the upper extremity of a post 14. The upper end of said lever is formed with a lug 34 thereon, which fits in a notch 35 in the lower edge of a link 36 pivoted vertically at one end on the door 13. The lower end of the lever 40 45 33 slides in a bore 34 formed in a block 35, said block being swiveled on the end of an arm 18 and free to turn on an axis at right angles to said bore. The unfolding of the bed operates through the arms 18, levers 33, 50 and links 36 to open the door 13, while the folding of the bed operates through said parts to close and lock said door. When it is desired to alter the normal inclination of the door 13 or close it, when the frame 15 is extended, it is only necessary to lift the 55 links 36 from engagement with the lugs 34 on the levers 33, thus freeing the door, which closes itself by gravity. Supplementary notches 35^a in the lower edges of the 60 links 36 may be selectively engaged with said lugs 34 to hold the door open to a greater or less degree, as desired.

Changes in the specific form of my invention, as herein disclosed, may be made 65 within the scope of what is claimed with-

out departing from the spirit of my invention.

Having described my invention what I claim as new and desire to protect by Letters Patent is:

1. A bed adapted to be folded vertically inside of a wall having an opening therein, also extended horizontally inside said wall or partially through said opening, said bed including head posts adjacent said opening, 75 a frame, the side members thereof being formed with longitudinal slots, said slots being enlarged at the head of the frame to form beveled catches, a beam revolubly supported at its ends in said posts and passing through said slots, the forward edges of said beam being beveled, at its intersections with said frame members, to fit said beveled catches, an arm on said beam, a counterbalancing spring stretched between said arm and post and serving to automatically engage the tiltable beam with the catches in said slides at the head of the frame and folding legs at the foot of the frame. 90

2. A bed including head posts adapted to be placed near an opening in a wall, said opening having a door hinged at the top thereof to said wall, a beam revoluble at its ends in said posts, a frame with side members slotted longitudinally to slidably receive said beam, means for releasably securing the head of the frame against sliding longitudinally on said beam, said frame being tiltable into upright position and slideable horizontally to permit the use thereof while wholly inside said wall or partially extended through said opening, an arm on the beam, a link attached at one end to the door, a lever pivoted near the middle thereof on a post, one end of the lever having a pivotal connection with said link and the other end thereof having a pivotal slideable connection with said arm, said arm, lever and link operating to close the door, when the frame is swung into upright position and to open the door, when said frame is returned to horizontal position. 100 105 110

3. A bed including head posts adapted to be placed near an opening in a wall, said opening having a door hinged at the top thereof to said wall, a beam revoluble at its ends in said posts, a frame with side members slotted longitudinally to slidably receive said beam, means for releasably securing the head of the frame against sliding longitudinally on said beam, said frame being tiltable into upright position and slideable horizontally to permit the use thereof while wholly inside said wall or partially extended through said opening, an arm on the beam, a link attached at one end to the door, a lever pivoted near the middle thereof on a post, one end of the lever having an adjustable pivotal connection with said link 115 120 125 130

and the other end thereof having a pivotal slidable connection with said arm, said arm, lever and link operating to close the door, when the frame is swung into upright position and to open the door, when said frame is returned to horizontal position.

4. A bed including head posts adapted to be placed near an opening in a wall, said opening having a door hinged at the top thereof to said wall, a beam revoluble at its ends in said posts, a frame with side members slotted longitudinally to slidably receive said beam, means for releasably securing the head of the frame against sliding longitudinally on said beam, said frame being tiltably into upright position and slideable horizontally to permit the use thereof while wholly inside said wall or partially extended through said opening, an arm on the beam, a link pivoted vertically at one end of the door and having a notch in the lower edge thereof, a lever pivoted on one of the posts, a lug on the upper end of the lever designed to receive said notch and detachably and pivotally join said link and lever, the other end of said lever having a pivotal slidable connection with said arm, said arm, lever and link operating to close the door, when the frame is swung into upright position and to open the door, when said frame is returned to horizontal position.

5. A bed including a support adapted to be placed near a wall with an opening therein having a door therefor, a frame tiltably and slidably carried at its head on said support and mechanism connecting the frame with said door for shifting the latter to close the opening, when the frame is swung into vertical position and to clear the opening, when the frame is swung into horizontal position for use, whereby said frame may be projected through the opening.

6. A bed including a support adapted to be placed near a wall with an opening therein having a door therefor, a frame tiltably and slidably carried at its head on said

support and mechanism connecting the frame with said door for shifting the latter to close the opening, when the frame is swung into vertical position and to clear 50 the opening, when the frame is swung into horizontal position for use, whereby said frame may be projected through the opening, said mechanism being designed to be rendered inoperative to permit independent 55 movements of the door and bed frame.

7. A bed including a support adapted to be placed near a wall with an opening having a door for closing the same, a frame tiltably and slidably carried at its head on said 60 support, the head of said frame being adapted to be projected through said opening and said door being adapted to form a canopy over the same, and mechanism, connecting said frame with the door to close the latter 65 when the frame is tipped vertically, and to shift said door into canopy forming relation removed from the opening, when the frame is swung into horizontal relation and in position to be projected through said 70 opening.

8. A bed including a support adapted to be placed near a wall with an opening having a door for closing the same, a frame tiltably and slidably carried at its head on said 75 support, the head of said frame being adapted to be projected through said opening and said door being adapted to form a canopy over the same, and adjustable mechanism connecting said frame with said door to 80 close the latter when the frame is tipped vertically and to shift said door into canopy forming relation removed from the opening when the frame is swung into horizontal relation and in position to be projected through said opening, the adjustability of said mechanism serving to alter the 85 normal relation between said door and bed frame.

In testimony whereof, I have signed my name to this specification.

LESLIE S. HACKNEY.
